(57) **CLAIM**

The ornamental design for a curtain rod bracket, as shown and described.

DESCRIPTION

FIG. 1 is a front perspective view of the right-side curtain rod bracket of a left and right side curtain rod bracket set according to the invention in which the bracket is attached by adhesive, the left side bracket being a mirror image thereof; FIG. 2 is a rear perspective view thereof, showing the adhesive;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
